UNITED STATES PATENT OFFICE.

LLOYD C. GLISSON, OF ATLANTA, GEORGIA.

AEROPLANE.

1,265,770.

Specification of Letters Patent. Patented May 14, 1918.

Application filed August 18, 1911, Serial No. 644,861. Renewed October 2, 1917. Serial No. 194,419.

To all whom it may concern:

Be it known that I, LLOYD C. GLISSON, a citizen of the United States, residing at Atlanta, in the county of Fulton and State of Georgia, have invented certain new and useful Improvements in Aeroplanes, of which the following is a specification.

This invention relates to aeroplanes. One of the principal objects is to provide a plane 10 of improved construction which shall constitute one of a series to be mounted in the framework, and which shall be controlled by a particular mechanism, also of novel construction, hereinafter described.

15 A further object is to provide a plane of such formation that it will be best adapted to meet the varying conditions under which it is designed to operate and which shall be properly and effectively braced so that the 20 control thereof shall be in no wise minimized by the warping or improper deflecting of portions of such plane.

A further object is to provide propelling means of improved construction whereby 25 said propelling means will assist in the balancing of the device as a whole, and a still further object is to provide lifting and propelling means having a similar function.

In the accompanying drawings forming 30 part of this application:

Figure 1 is a view of the device in side elevation.

Fig. 2 is a bottom plan view.

Fig. 3 is a view, partly in vertical section, 35 of the mechanism for controlling the planes.

Fig. 4 is a view in vertical section of the means for supporting the structure shown in Fig. 3.

Fig. 5 is a horizontal section on a line 40 passing through the lower worm wheel in Fig. 3.

Fig. 6 shows the means for controlling the cables of the rudders.

Fig. 7 is a vertical section through two 45 of the planes, with the controlling means in elevation.

Fig. 8 is a vertical section through the framework at a point in proximity to the forward propeller.

50 Fig. 9 is a plan view of one of the transverse planes.

Fig. 10 is a view in elevation and section showing the manner of connecting the trans-

verse planes to the longitudinal shaft on 55 which each is mounted.

Fig. 11 is a view of one of the channel ribs for bracing the planes.

Fig. 12 is an elevation of another form 60 of the machine.

Fig. 13 is a detached view showing means for operating the rudders.

Fig. 14 shows certain details in connection with the operation of the propellers.

Fig. 15 is a vertical section of one of the 65 funnel members.

Fig. 16 is a detail of structure shown in Fig. 13.

Fig. 17 is a detailed view including a 70 clutch.

In carrying out my invention, I provide a suitable framework composed of transverse sections or separate frames shown in Fig. 8 and including uprights 10, arches 15, and lower transverse members 16. A transverse 75 member 17 extends between uprights 10 at the crown of the arch, and connected with vertical members 5, 6 and 7 and the upper portions of members 10 are the transversely arranged planes 18 constituting the upper 80 planes of the several series. The frames also include uprights 3 and braces 4 and 5.

In Fig. 1 it will be observed that I have shown four series of planes each consisting of three planes mounted one above the other 85 and connected at their edges by cables, in order that they may be simultaneously operated for the purpose of varying their inclination. These planes are provided with transverse bracing members 19 and are 90 pivoted at points 20.

The upper transverse plane 18 of each series extends above the gas bag mentioned below. The central transverse plane 21 of each series extends below the gas bag and 95 above the car body, and the bottom plane 22 of each series extends below the car body.

The several vertical and transverse frames are spaced apart at each side by longitudinal bars 25 and 26, the former being arranged 100 above the latter and providing a space between the two longitudinal bars, extending the full width and length of the framework as a whole. It will be understood that bars 25 occupy corresponding positions on opposite 105 sides of the framework.

At the central portion of the framework

and on each side thereof is a substantially rectangular portion formed by tubular members 27, the central portion of which members extends approximately parallel with the bars 26. Bearings 28 and 29 are oppositely located in the said tubular members 27 and 26. Propellers hereinafter referred to are journaled within these bearings. Between the aforesaid bearings and the opposite ends of the framework are similar devices in which horizontally arranged propellers are located. Three horizontal propellers are arranged on each side of the framework and are driven in the manner described below. Connected with the tubular members 27 and extending diagonally to the adjacent vertical transverse frames are braces 30 and 31. At the lower portion of each vertical transverse frame, wheels 32 are mounted on axles 32' for supporting the device when upon the ground.

The upper portion of the framework comprises a horizontal rod 34 extending to an end rod 35 and being braced by a curved member 36. The lower longitudinal bar 37 is connected with bar 35 by a diagonally arranged bar 38 and from bar 38 vertical bars 39 and 40 extend to bar 25 previously mentioned. Between said bars 39 and 40 vertically arranged propellers are journaled on each side of the machine.

At the opposite end of the framework the construction is substantially the same and the propellers are similarly arranged.

A large propeller 41 is carried at the extreme rear end of the machine, beyond the framework, and is suitably journaled therein at 42, being driven by an engine 43 of the rotary internal combustion type, although it is evident that any other type of engine may be employed. At the forward end of the machine a propeller 44 is similarly mounted and driven.

The propellers 41 and 44 are carried by shafts 45 and 46, centrally mounted, and are driven by engines provided especially for the purpose. The remaining propellers are driven by other engines mounted centrally of the framework and between the engines already described. Shafts 50 and 51 located in the sides of the framework and extending longitudinally thereof are driven from engines 52 and 53 which have connection with the shafts 50 and 51, by straight belts and by twisted belts, in order that the said shafts 50 and 51 may be driven in the required direction. I propose to operate the engines in opposite directions, in order to obtain the benefit of the balancing effect produced thereby. On side shafts 50 and 51 pulleys 55 are mounted, and are connected by belts 56 with the pulleys 57 carried by the engine shafts. The vertically arranged propellers 60 are carried by the ends of shafts 50 and 51 and they are driven

directly thereby, while horizontally arranged propellers 61 mounted within the rectangular frames above referred to, are driven through the medium of gears 62 and 63 which may, if desired, be of raw hide. Clutches are shown conventionally at 65.

The car is indicated by the numeral 70, and is mounted in the position shown in Fig. 1. Within this car are means for controlling the several planes and the rudders as hereinafter mentioned. In Fig. 1, I have shown vertically arranged rudders 71 located at the ends of the frame-work below longitudinal plane 150. These rudders are operated by the mechanism shown in Fig. 6. In the modification shown in Figs. 12 and 13 horizontal rudders 72 are also employed, there being no change however in the operation of rudders 71. An additional hand wheel 79 operates the horizontal rudders 72 and this may be conveniently mounted on a tubular member 80 carried by shaft 77 operating rudders 71. Rudders 71 are controlled by cables 73 and 73', and the rudders 72 by means of cables 74 and 75 and levers 76, connected with the cables last mentioned, and with the rudders 72. A vertical shaft 77 carries a wheel 78 on the lower end thereof, which wheel is adapted for control by the aviator, and a second wheel 79 is carried on a tubular member 80 and carries a pulley 81 around which cable 74 passes. Cable 73' passes around pulley 81 on shaft 77. The construction in Fig. 13 is duplicated at the opposite end of the framework and affords effective control of all the rudders from the points indicated. In Fig. 13 all of the rudders are for convenience shown as being controlled from one point. In Fig. 6 one of the cables 73 and 73' passes about the vertical shaft 77 at one end of the structure and the other of said cables passes about the other of said shafts 77, cables 73 and 73' being connected respectively with the ends of levers 76.

The central plane of each of the vertically arranged series is provided with a lever 85 having connection with a longitudinally arranged rod 86. Two of these rods are provided, the second being designated 87 and connecting the several series of planes at one end of the structure, while rod 86 connects the series at the opposite end. Connecting bars 88 and 89 are secured to the ends of the longitudinal bars and are connected at 90 and 91 with a vertical rod 92 carrying a weight 93 at its lower end, said vertical rod being inclosed in tube 92' pivoted at 94, and the construction as a whole constituting an equilibrator. The movement of this device is cushioned by means of cylinders 95 and 96 arranged horizontally and having pistons therein connected with bars 97 and 98, which bars are also connected with the vertical bar 92. The operation of

this construction will be readily understood when it is considered that the tilting of the forward end of the entire structure will produce a corresponding movement of the pendulum of the equilibrator, and through the medium of rods 86 and 87 will tilt the central planes 21 of each of the four series and thereby position said planes and the other planes of the series at the proper angle.

In Fig. 3, I have shown in detail the means for connecting rods 88 and 89 with the central rod 92 carrying the weight 93 at its lower end. Said rods 88 and 89 are provided with casings 100 connected with the ends thereof, said casings being threaded at 101 for the reception of threaded members 102 carrying hand wheels 103. Threaded members or rods 102 connect at their ends, located within the casings, with members 104 having connected thereto and at right angles therewith rack bars 105 arranged to engage gears 106 rotating with gears 108 which in turn engage worms 107 in casings 100' on the aforesaid central rod 92. A ball bearing coupling 93' connects rod 92 and tube 92'. The relative position of the parts is shown in Fig. 7 and it will be understood that the operation of hand wheel 103 effects the movement of rod 89 with reference to the vertical rod 92 of the equilibrator. A similar function is performed by the operation of the other hand wheel 103 with reference to the position of rod 88. The hand wheel 110 provides for the rotation of the central vertical rod 92 and for the resulting operation of both of the wheels 106 for the simultaneous positioning of rods 88 and 89 with reference to the central rod 92.

In the upper portion of the structure, above bar 25, a gas bag 115 is located, this bag extending, if desired, the full length of the structure.

Vertical planes 125 and 126 are located respectively at the ends of the framework.

These planes as shown in Fig. 1 aid in maintaining the stability of the structure.

The transverse planes 18, 21, and 22 are provided with stiffening tubes extending transversely thereof and indicated by 75'. This construction is illustrated in Fig. 10. These tubes are approximately rectangular in cross section and extend from the front edge to the rear edge of each plane, and are spaced apart a suitable distance as shown in Fig. 9. Extending parallel with the stiffening members just mentioned are channel members 76' which are tapered slightly from the central longitudinal axis of the planes toward each edge, and are provided with a beveled portion 77' which abuts the edge of a deflecting device 78' connected with the forward edge of the plane. [Fig. 7.] This deflecting device is regarded as be-

ing especially effective in reducing the atmospheric pressure above the surface of the plane, so that the latter may encounter the least possible resistance. Extending longitudinally of the central axis of the plane is a tubular member 19 passing through the aforesaid channel members, and through eye portions 80' of members 5, 6, 7 and 10 of the vertical frames. Tubular ribs 75' and channel members 76' are brazed along the line 81', for forming the structure shown in Fig. 10.

Tie wires 160 extend transversely of the machine, above the upper planes, and longitudinal tie wires 161 extend from end to end thereof.

The planes of each vertical series are connected at their edges by cables or cords 162, so that all of the planes of a given series will move together. Pulleys 164 on the framework accommodate cords 165 connected with the edges of each plane, at the ends of the latter, and the central plane of each series is strengthened by braces 166.

The vertical plane 140 extends longitudinally of the gas bag and centrally thereof, and is designed to prevent the rolling of the structure on its longitudinal axis, due to lateral wind pressure, if the bag collapses or becomes damaged. Inner arched members 141 hold the material of the gas bag normally in an expanded position, even when not filled or when not entirely filled with gas. When the bag is intact and is filled, it will of itself serve to balance the structure as a whole, the bulk and weight above and below the central longitudinal plane 150 being suitably proportioned.

This central longitudinal plane extends substantially the full length of the structure and horizontally thereof above the main longitudinal axis of the machine.

The plane last mentioned projects laterally beyond the edges of the bag, and the plane coöperates with the central transverse planes in a novel manner, by reason of the particular construction of the transverse planes and the means for controlling the same. The transverse members are termed planes for convenience, this being the accepted term for a supporting and elevating device having the function stated.

Plane 150 aids in forming a protecting zone for the central transverse planes 21 and largely prevents them from being acted upon by currents of air moving in a direction other than the direction traveled by the machine. The propellers at the sides of the frame also aid in protecting these central transverse planes from such currents.

The car body is boat shaped and is constructed to float when a descent is made on the surface of a body of water.

The end portions of the framework are formed as shown in Fig. 2, curved members 133

167 being braced by transverse braces 168. Another transverse member 169 aids in supporting shafts 50 and 51. Converging braces 170 are also shown in Fig. 2.

5 Fig. 12 shows a modification in which a lower gas bag 130 and six series of planes are employed. The driving mechanism is substantially that employed in the form above described, but in connection with the 10 horizontal propellers I employ funnels 185 slightly tapered as shown. These funnels constitute air ducts for the horizontal propellers. Engine 175 drives propeller shaft 176 and side shafts 177 through the medium 15 of belts 178.

It will also be observed that in this form the cylinders 95' and 96' for equalizing the movement of the vertical rod connected with the weight, are connected at the upper end 20 of said rod. The horizontal and vertical rudders are controlled by the mechanism shown in Fig. 13 and previously described.

The car body is designated 180.

While I have described my invention in 25 detail, I do not wish to be limited to the exact construction, but may make such changes or alterations as fall within the scope of the appended claims.

What I claim as new and desire to secure 30 by Letters Patent of the United States, is:

1. In a device of the class described, a framework, a plurality of planes mounted therein and transversely thereof, certain of said planes being arranged above others 35 therein forming series, means for connecting the corresponding edges of the several planes in a given series to permit the simultaneous and uniform control of all the planes in a series, bars extending longitudinally of the framework, a weight mounted within the framework, a rod for carrying said weight, adjustable means for connecting the aforesaid bars and rod and including telescoping members, one of which is 40 connected with the weight and bars and the other with a supporting device, and means for cushioning the movement of the weight and the devices connected therewith.

2. In a device of the class described, a 50 framework, a plurality of planes mounted therein, and extending transversely thereof, certain of said planes being arranged in series and adapted for simultaneous adjustment, rods extending longitudinally of the 55 framework, a substantially vertical rod pivoted within the framework, means for connecting the aforesaid rods with the vertical rod on opposite sides of the pivotal point and including a casing, rack mechanism therein independent of the casing, and a gear between the rack and vertical rod and imparting movement from the latter to the former, and means for cushioning the movement of the vertical rod.

3. In a device of the class described, a 60 framework, a plurality of planes mounted therein, rods extending longitudinally of the framework and having connection with said planes, a substantially vertical rod, weighted, and pivoted within the framework, 70 and means for connecting the aforesaid rods with the vertical rod on either side of the pivotal point, said means comprising members movable lengthwise with reference to the longitudinal rods which they 75 respectively control, rotatable means for engaging the lengthwise movable means, said rotating means having a worm and gear connection with the vertical rod.

4. In a device of the class described, a 80 framework, a plurality of planes mounted therein, a rod weighted and mounted substantially vertically within the framework, means for pivoting said rod, means connecting the vertical rod with the aforesaid 85 planes, said means comprising members movable lengthwise of the connecting means which they respectively control, and rotatable means connected with the lengthwise movable means and having worm and gear 90 connection with the vertical rod.

5. In a device of the class described, a framework comprising a plurality of sections spaced apart and vertically arranged, longitudinal means connecting portions of 95 said sections and outlining a central opening extending lengthwise and transversely of the framework, rudders mounted within the said opening supporting and balance-controlling flanged planes arranged transversely within the opening and above and 100 below the framework, vertically mounted controlling shafts, wheels carried thereby, and cables connecting the said rudders and wound upon said shaft.

6. In a device of the class described, a framework comprising a plurality of sections spaced apart and vertically arranged, longitudinal means connecting portions of 110 said sections and outlining a central opening extending lengthwise and transversely of the framework, supporting and balance-controlling flanged planes arranged transversely within the opening and above and 115 below the framework, vertically and horizontally arranged rudders mounted within the said openings, vertically mounted controlling shafts, wheels carried thereby, and cables connecting the said rudders and wound upon said shaft.

7. In a device of the class described, a framework, a plurality of flanged planes arranged therein and extending transversely thereof, said planes being concave on their underside and being braced transversely, 125 and means for controlling a plurality of planes in a series so that the edges thereof shall have the same inclination and means

controlling a plurality of series so that the edges of planes of different series shall present unequal resistances.

8. In a device of the class described, a framework, driving mechanism mounted in the lower portion thereof, a plane extending transversely and longitudinally of the framework above said lower portion and means above said plane for preventing the sidewise tilting of the framework under a given lateral wind pressure and a collapsible member, said means being located within the collapsible member and arranged to partly support the latter.

9. In a device of the class described, a framework, propelling means located in the lower portion thereof, lifting means in the upper portion, a plane extending below the lifting means and projecting laterally thereof, and means above said plane for preventing tilting of the structure on its longitudinal axis under a given lateral wind pressure, a collapsible member and arched members coöperating with the means last mentioned for supporting the collapsible member.

10. In a device of the class described, a framework, a lifting device carried within the upper portion thereof, a plane extending below said device, propelling means carried by the framework, curved transverse planes coöperating with the plane first mentioned, deflecting devices thereon, means for

controlling the inclination of the transverse planes and their deflecting devices with reference to the first mentioned plane, and means for controlling all of the planes simultaneously.

11. In a device of the class described, a framework, a lifting device carried within the upper portion thereof, a longitudinal plane extending below said device, propelling means carried by the framework, curved transverse planes coöperating with the plane first mentioned, deflecting devices on the curved planes, means for controlling the inclination of certain of the transverse planes and their deflecting devices with reference to the first-mentioned plane, and independently of the other transverse planes, and means for controlling automatically and simultaneously all of the planes set by the controlling means first mentioned.

12. In a device of the class described, a framework, a plane mounted therein, a tubular device rectangular in cross section for bracing said plane in one direction, and channel-member rectangular in cross section for reinforcing the tubular device throughout its length.

In testimony whereof I affix my signature in presence of two witnesses.

LLOYD C. GLISSON.
